UNITED STATES PATENT OFFICE.

HANS NIELSEN, OF DAWSON CREEK, BRITISH COLUMBIA, CANADA.

WIRE STRETCHER.

Application filed January 19, 1925. Serial No. 3,452.

To all whom it may concern:

Be it known that I, HANS NIELSEN, a subject of the King of Great Britain, residing at Dawson Creek, in the Province 5 of British Columbia, Canada, have invented certain new and useful Improvements in Wire Stretchers, of which the following is a specification.

This invention appertains to tools for facilitating the construction of wire fences and the like and the primary object of the invention is to provide a novel wire stretcher, which can be readily and quickly associated with one of the fence posts against slipping 15 movement and which embodies novel means for tightly pulling the wire against the said post so that the wire can be rigidly secured to the post.

A further object of the invention is the 20 provision of a novel frame slidably supporting the wire stretching lever and a novel clamp carried by one end of the frame for engaging the fence post or other rigid support.

A still further object of the invention is 25 to provide an improved wire stretcher of the above character, which will be durable and efficient in use, one that will be simple and easy to manufacture and one which 30 can be placed upon the market at a small cost.

With these and other objects in view, the invention consists in the novel construction, arrangement and formation of parts, as will 35 be hereinafter more specifically described, claimed and illustrated in the accompanying drawings, in which drawings,

Figure 1 is a top plan view of the improved wire stretcher,

Figure 2 is a side elevation of the same, 40 Figure 3 is a transverse section through the wire stretcher taken on the line 3—3 of Figure 1 looking in the direction of the arrows.

Referring to the drawings in detail, where- 45 in similar reference characters designate corresponding parts throughout the several views the letter A generally indicates the improved device, which comprises a frame 50 10, a clamp 20 disposed at one end of the frame for engaging the rigid support such as a fence post and the fence wire tightening member 30 mounted for a step by step move- 55 ment on the frame.

The frame 10 comprises a pair of spaced 60 parallel rack bars 11 and 12 and a pair of

spaced guide bars 13 and 14 which are disposed below in spaced relation to the rack bars 11 and 12. An end block 15 is arranged 60 at one end of the frame and is rigidly connected to the terminals of the rack bars 11 and 12 and the guide bars 13 and 14. As clearly shown in Figure 3 of the drawing the forward ends of the rack bar 11 and the guide bar 13 are integrally connected by a 65 bridge plate 16.

The forward end of the frame carries a pair of spaced transversely extending guide plates 17 and 18 and these guide plates are riveted or otherwise secured to the forward 70 terminals of the rack bars 11 and 12 and the guide bars 13 and 14 and the plates extend laterally of the rack bar 12 and the guide bar 14. These plates are normally held in 75 spaced relation by a suitable spacing block 19 which is disposed in spaced relation to the bridge plate 16. As clearly shown in Figure 1 of the drawing the forward edges of the guide plates 17 and 18 are provided 80 with equi-distantly spaced diagonally extending bayonet slots 21 for a purpose which will be hereinafter more fully described.

The novel clamp 20 comprises a substan- 85 tially circular rigid jaw 22 and a substan- 90 tially semi-circular movable jaw 23. The rigid jaw 22 is provided with a shank 24 which is disposed between the spacing block 19 and the bridge plate 16 and is preferably 95 secured to the plate by the same bolt or rivet utilized for connecting the guide plates 17 and 18 to the rack bar 11 and the guide bar 13. The forward ends of the jaws 22 and 23 are provided with laterally extending 100 ears 25 to permit the opening and closing thereof and to facilitate the placing of the jaws around a fence post. The inner faces 105 of the jaws are provided with biting teeth 26 for gripping the fence post. The inner end of the movable jaw 23 is provided with a rigid shank 27 which is adapted to ride 110 between the spaced guide plates 17 and 18 and this shank receives a suitable pin or bolt 28 for fitting in any of the inclined bayonet slots 21 to permit the initial adjust- 115 ment of the movable jaw 23 relative to the stationary jaw 22. The shank of the movable jaw also carries a hand screw 29 which is adapted to engage the shank of the rigid jaw.

When the wire stretcher is to be associated with a fence post the forward pin 28 is slipped into one of the bayonet slots 21

so that the rigid jaw 23 will lie in relative close proximity to the post after which the hand screw 29 is manipulated which will swing the jaw on the bolt or pin 28 5 into intimate contact with the post for firmly holding the post between the jaws 22 and 23.

The wire stretching member 30 comprises a movable slide block 31 which is disposed 10 between the rack bars 11 and 12 and the guide bars 13 and 14. The upper and lower ends of the slide block 31 carries flange plates 32 which engage the outer faces of the rack bars and the guide bars 15 for holding the block in position. A hand lever 33 is rockably mounted at a point equi-distant its ends upon a suitable bolt or pin 34 carried by the said block 31 and the lever on each side of the rack bars 11 20 and 12 is provided with a pivoted dog 35 for engaging the teeth of the rack bars. These dogs 35 are normally urged into engagement with the rack bars by suitable springs or the like 36. Any preferred type 25 of clamp 37 is carried by the slide block 31 for receiving the fence wire which is to be stretched.

In use of the improved tool the frame is associated with the fence post and the dogs 30 from out of engagement with the teeth of the rack bars and the slide block is slid toward the clamp. The wire to be stretched is now moved into engagement with the clamp 37 and by swinging the lever 33 from 35 first one side and then the other, the slide block can be moved in a step by step movement thus bringing about the stretching of the fence wire.

From the foregoing description it can be 40 seen that I have provided a novel wire stretcher of exceptionally simple and durable character which will effectively accomplish the desired results.

Changes as to details may be made without departing from the spirit or the scope 45 of this invention, but:—

What I claim as new is:—

1. In a wire stretcher, a frame comprising a pair of spaced parallel rack bars and 50 a pair of spaced parallel guide bars disposed below and in parallel relation to the

rack bars, a pair of spaced laterally extending guide plates carried by the forward terminals of the rack bars and guide bars, the forward edges of the guide plates being 55 provided with a plurality of equi-distantly spaced bayonet slots, a slide block mounted between the rack bars and the guide bars, flange plates carried by the upper and lower ends of the slide block engaging 60 the outer faces of the rack bars and the guide bars, a lever rockably mounted at a point equi-distantly its ends on the slide block, spring pressed dogs carried by the lever for engaging the rack bars, a wire 65 clamp carried by the slide block, and a clamp carried by the forward end of the frame for engaging a fence post including an arcuate rigid jaw and an arcuate movable jaw, a shank formed on the rigid jaw 70 rigidly secured to the frame, a shank formed on the movable jaw, a pin carried by the shank arranged to engage in any one of the bayonet slots, and a feed screw carried by the shank of the movable jaw arranged to 75 engage the shank of the rigid jaw, as and for the purpose specified.

2. A wire stretcher comprising a frame including a pair of spaced parallel rack bars, a pair of spaced laterally extending 80 guide plates disposed at the forward end of the rack bars, a slide block mounted between the rack bars, a lever rockably mounted at a point equi-distantly its ends on the slide block, spring pressed dogs carried by the lever for engaging the rack bars, a wire clamp carried by the slide block, and a clamp carried by the forward end of the frame for engaging a rigid support including an arcuate rigid jaw and an arcuate 85 movable jaw, a shank formed on the movable jaw and received between the guide plates, and means associated with the shank and guide plates for adjusting the movable jaw toward the rigid jaw. 90

In testimony whereof I affix my signature in presence of two witnesses.

HANS NIELSEN.
